BIAS CUTTING MACHINE

David Balk, New York, N. Y., assignor to Superba Manufacturing Co., Inc., New York, N. Y., a corporation of New York

Application July 26, 1941, Serial No. 404,137

18 Claims. (Cl. 164—61)

My invention relates to improvements in bias cutting machines, vertical, horizontal or angularly positioned for transforming spirally a roll of tubular material of any kind into a wide continuous bias strip, and has for its principal object to produce a machine capable of cutting such a strip which will be bias to the weave of the fabric.

Several machines especially constructed for this purpose are and have been in use for many years, but in each instance the machine is complicated in construction and expensive to build and maintain. As a result, the field is very restricted because only users having large quantities of work are in a position to employ expensive machinery of this character.

With this in mind, it is a further object of the present invention to provide a cutting machine of this character, in which all parts are of the simplest design and their number is reduced to a minimum commensurate with the operations necessary to produce accurate and efficient results.

Bias cutting machines of the accepted type are restricted to angular adjustment of the cutting element and feeding mechanisms between the sides of an angle, defined by a horizontal line and a perpendicular line at the right of the vertical axis of the tubular material in its movement through the machine. In other words, the cutting element is capable of cutting spirally only in a clockwise direction about the tubular material. This is a limitation when it comes to cutting through the material, which under certain conditions allows the cut edges and the seams to turn back upon themselves and produces a bump in the bias strip, as this is transmitted to the winding or rolling machine.

The present invention comprises an improved mandrel for a machine of this character combined with a system of feeding mechanism and interpositioning of the cutting element, whereby the spiral feeding and cutting of the tubular material may be effected either in a clockwise or counter-clockwise direction, depending upon the nature, texture or weave of the material. Due to the nature of the material or the commercial finishes applied to it in the course of manufacture, there is a tendency for the cut bias strip to curl either with the face of the seam or against it. This curling will determine whether the material has to be cut clockwise or counter-clockwise. Once properly cut, the bias length will be more quickly and properly transmitted to winding or rolling machines. This will also apply to sliced narrow strips used for pressed fold bias tapes, and

to flat bias strips for seaming operations. If the cut is contrary to the nature of the cloth, the tapes will not press flat, and in the flat narrow sliced strips used for seaming and binding, the seam ends will then snag or fold over when fed through gauges. Clockwise or counter-clockwise cutting will correct these faults.

A further object of the invention is to provide a bias cutting machine of this character with an overhead swivel supporting element for the roll of tubular material, which element is positively guided in its rotary movement, to allow uniformly spiral feeding of the material without tilt or distortion before and as it reaches the mandrel, feed rollers and lastly the cutting element. This will make the cut edges of the material straighter and when rolled ply upon ply, will make a roll of bias cloth uniformly perfect at both ends, eliminating excessive trimming waste, the overhead swivel being adjustable with respect to the cutting machine to accommodate different widths of tubular material and position the same coaxial of the mandrel in any of its adjusted positions.

A still further object of my invention is to provide a mandrel, of the character hereinafter described, of sections having relatively flat sides upon which the feeding and cutting operations on the tubular material are performed, for the purpose of increasing the capacity of the machine and reducing the number of parts ordinarily used to carry out the operations and of simplifying the construction of the remaining parts.

A still further object of this invention is to support the flat sided sections of the mandrel in such a way as to enable one of the sections to be fixed and to carry the cutting element and one set of feeding devices, while the other section is adjustable towards and away from the fixed section to accommodate different diameters of tubing and carries another set of feeding devices co-operating with the first set to feed the tubing downwardly and spirally along the cutting edge of the cutting element.

Still a further object is to provide a support for the material feeding in any position of the cutter, without drag or tilt of the material roll, or strain on the mandrel and its functioning parts while the mandrel is operating.

Another object is to provide a support for the material to induce a smooth feeding and cutting operation which will not cause any stretch or pull of the material while in process, nor break up or distort the finish of the material.

An additional object is to provide means to combine simultaneously a clockwise or counter-

clockwise motion in both the supporting means and feed for the mandrel.

I accomplish the objects of my invention by means of certain combinations and arrangements of parts hereinafter described, the nature of the invention being more fully explained in the following description, taken with the accompanying drawings, which present one or more embodiments of the mechanism. The disclosure is of course explanatory only and the constructions shown are given merely as examples. In practice I reserve the right to make substitutions and alterations in the type, shape, size and arrangement and manner of use of the various members, without departing from the principle of the invention or exceeding the broad and general aim and range thereof, or the broad meanings of the terms set forth in the appended claims and illustratively exemplified in the accompanying drawings, in which:

Figure 1 is a side elevational view of the machine showing the mandrel open to accommodate the roll of tubular material of greatest width;

Figure 2 is a substantially vertical sectional view of the machine taken on lines 2-2 of Figure 1;

Figure 3 is a substantially transverse sectional view of the machine taken on lines 3-3 of Figure 1;

Figure 4 is an end elevational view showing the fixed section of the mandrel and the feeding and cutting attachments;

Figure 5 is an elevational view of a slightly modified form of overhead support for a roll of tubular material of extra width;

Figure 6 is a top plan view of a mandrel in which the sections are shaped to cooperate to produce the flat sides;

Figure 7 is a side elevational view of the mandrel sections shown in Figure 6; and

Figure 8 is a side elevational view of a still further modified form of mandrel showing accommodation for a single feed unit to a side.

Referring to the drawings and particularly to Figures 1 to 4, 10 denotes the base of the supporting structure of the bias cutting machine. The base comprises a flat floor plate having a raised motor platform 11 and upright standard 12 at one end and a second upright standard 13 at the other end. The standards 12 and 13 are disposed transversely of the longitudinal axis of the base 10 and parallel to each other. Supported at their ends in the standards are spaced guide bars or tracks 14 and 15; the bar 14 is preferably cylindrical in shape and is disposed above the bar 15 which is preferably square in transverse section and is provided with a series of graduations on one side to allow for properly setting the mandrel for different widths of material.

The standard 12 adjacent its opposite ends is provided with upright supporting rods 16 upon which are mounted the fixed sections 17 of the mandrel over which the tubular material A is guided in its downward spiral movement, as hereinafter described. Slidably mounted upon the bars 14 and 15 and capable of adjustment to any position between the standards 12 and 13 is a carriage 18 comprising a rectangular block of approximately the length of the standard 12, the block having openings to receive the bars 14 and 15 and being provided with castors 19 on its under side to contact with the surface of the base plate 10 and give rolling support to the carriage. The carriage 18 may be locked in any

position along the rods 14 and 15 by means of suitable set screws 18'. Mounted upon the opposite ends of the top of the carriage 18 are supporting rods 20 which carry at their upper ends the movable section 21 of the mandrel.

The mandrel sections 17 and 21 are similar in shape, each thereof comprising an upright flat center portion and integral curved ends 22. In other words, the sections are virtually U-shaped. In transverse section, the closed side thereof being elongated to provide the flat side. The particular advantages of constructing a mandrel of sections having flat sides is that the peripheral dimensions of the ordinary mandrel can be greatly increased without requiring any more space in the axial direction of the machine than that required of the present type of cylindrical mandrel. The large peripheral dimension of a mandrel in this art allows a tubular material to be accommodated which may be much greater in diameter than usually used with a consequence that strips of greater length may be cut from a single roll. The bottoms of the sections 17 and 21 are closed at opposite sides of the centers by walls 23 which rest upon and are attached to the upper ends of the supporting rods or posts 16 and 20. The upper ends of the sections are beveled inwardly to form a semi-conical guide for the tubular material. As illustratively exemplified in Figures 1 and 3, the open inner sides of the mandrel sections face each other so as to form in any relative positions thereof a core over which the tubular material may be guided.

The feeding mechanism for moving the tubular material downwardly and spirally over the mandrel includes two positively driven feed rollers 24 and 25 and corresponding coacting rubber pressure rollers 26 and 27, to respectively engage the inner and outer faces of the material.

Rollers 24 and 26 are disposed obliquely at an angle to the vertical axis of the mandrel to exert an angular pull on the material in a clockwise direction to effect the spiral feeding of the material over the mandrel. Rollers 25 and 27 are disposed obliquely at an angle to the axis of the mandrel to exert an angular pull on the material in a counter-clockwise direction. As illustrated, the positively driven feed rollers 24 and 25 are located on the sections of the mandrel with their peripheries extending slightly through openings 28 and 29 in the sections. The pressure rollers 26 and 27 are supported for rotation in yoke-shaped bearing elements 30 disposed exteriorly of the mandrel and supported on rotatable brackets 31 mounted on the upper ends of upright rods 32. The rods 32 at the stationary end of the mandrel are supported on brackets 33 on the standard 12, while the rods 32 of the adjustable section are carried in brackets 34 projecting from the supporting rods 20.

In operation, it will be seen that only one pair of feeding and pressure rollers can be operated at one time in each section, because one pair engages the material to move it spirally in a clockwise direction, while the other pair causes the material to move in counter-clockwise spiral direction. Consequently, diametrically opposite pairs of rollers must operate together and a means whereby a single driving mechanism may be used to operate separately the driven rollers of a single section is illustrated particularly in Figures 1 to 3. Power from a motor 35 mounted on the motor block 11 is transmitted from a small pulley 36 on the motor shaft to a larger pulley 37 by means of a belt 38. The pulley 37

is fixed on the end of a shaft 39 which is disposed longitudinally of the machine and at an elevation just above the top of the standards 12 and 13 and carriage 18. The shaft 39 is mounted in bearings 40 on the standards 12 and 13 and its mid-portion 41 is either square in transverse section or provided with a key running throughout its length. The portion of the shaft adjacent the bearing 40 of the stationary standard 12 carries a bevel gear 42 in mesh with a second bevel gear 43, which is operated above and at right angles to the first gear and which is supported in a bearing bracket 44 projecting from and integral with the bearing 40. Bevel gear 43 turns a vertical shaft 45 upon the upper end of which is mounted one member of a universal joint 46, the upper member thereof being attached to a drive shaft 47 which projects upwardly at an angle to align itself with one or the other of the stud shafts 48 operating the feed rollers 24 and 25. The shaft 47 enters the space directly in back of the flat wall 21 through the space between the bottom walls 23 and is aligned with the axis of either feed roller. The shaft 47 is attached to the stud shaft 48 by means of a collar or union 49 which embraces both shafts and is fixed to each by set screw connections 50. The stud shafts 48 are journaled in bearings 51 attached to the inside of the mandrel section, each bearing 51 supporting a set of bevel gears 52, one thereof being carried in each instance by the shaft of a feed roller 24-25, which are rotatably mounted in brackets 53 on the section at opposite ends of the opening 28-29. To change the drive from clockwise to counter-clockwise, the shafts 47 are swung from side to side and attached by means of the collars 49 to the stud shafts 48 and motor 35 is reversed in its direction of rotation.

The feed rollers of the adjustable section 21 are driven in exactly the same manner as those of the stationary section 17, except that the bevel gear 42' is provided with a square axial opening to receive the square shaft 39 to allow the gear to be moved along the same. The bracket 40 supporting gears 42' and 43 is mounted on the upper side of the carriage 18 and moves with it as the adjustable section of the mandrel is moved.

It will be necessary for proper operation of the feeding mechanisms that the pressure roller of the pair not in use be moved away from its feed roller and this is done by simply swinging the pressure roller of each section about on its bracket 31 and out of the way of the material moving on the mandrel.

The cutting mechanism is illustratively exemplified in Figures 3 and 4 and comprises an angularly disposed arm 54 at the upper end of a standard 55, which is supported from the base 56 on the standard 12. A brace 57 is connected at its ends to the standard 55 and adjacent supporting rod 32 to hold the cutting mechanism in rigid position. Two base members 58 are provided, one on each side of the bearing bracket 60 for the shaft 29, as shown in Figure 4, so as to permit the standard 55 to be transposed from one base to the other depending upon the direction of the cut to be made in the material. The arm 54 has mounted thereon a motor 59 to the shaft 59 of which is secured a disk knife 60. The axis of the shaft 59 and disc 60 is disposed parallel to the axes of the feeding and pressure rollers operating on the material. The cutting edge of the disc 60 is disposed at its point of contact with

the material at an angle to the axis of the mandrel and at an angle coincident with the angularity of the rollers of the feed mechanism and at a point midway between the openings 28 and 29 in the flat side of the section 17. The cutting disc 60 depends from the motor and its cutting edge enters the arm of a slot 61 in the mandrel, the slot being a cross in shape in which the arms thereof branch out at suitable angles from each other. This construction brings one pair of arms of the slot 61 at the desired angle to the other pair and parallel with the axes of the pair of rollers cooperating with the disc 60 to feed the material past the latter. The two possible positions of the cutting mechanism are shown in Figure 4, the arrangement for cutting along a clockwise spirally moving material being shown in full lines while the counter-clockwise arrangement is illustrated in dotted lines.

The overhead support for the roll B of tubular material A to be fed to the machine in a downwardly spiral direction is shown in Figures 1 and 2 and comprises an inverted V-shaped bale or frame 62, the depending side arms of which are provided with spaced guide rods 63 between their free ends and at approximately the mid-positions of the arms they are provided with inclined open ended slots 64 to removably receive a spindle 65 of a core 66 in the center of the roll B. The center of the closed end of the bale is provided with a pivotal connection 67 to a hanger 68 the opposite ends of which are attached to a bracket 69. The bracket is a circular channel piece and at four evenly spaced points about its periphery are depending sockets 70 supported upon the upper ends of upright supports 71, the lower end of the latter being provided with castors 72 rolling upon the floor outside the base plate 10. The bale or frame 62 is prevented from rocking in its rotary movement as the material A is being unwound from the roll B by means of a pair of rollers 73 mounted on shafts 74 projecting outwardly from the side arms of the bale and running on a circular track 75, which is supported in the lower side wall of the channel bracket 69. The overhead support for the roll B is movable with respect to the cutting machine in order to allow for different widths of rolls, the transverse axis of which must be disposed coincident with the axis of the mandrel in order to permit rotary movement of the roll and uniform downward spiral movement of the material about the sections of the mandrel.

In use and operation of the machine it must first be determined whether the movement of the material is to be in a clockwise or a counter-clockwise spiral direction. The roll of tubular material supported overhead on the bale 62 is then unwound to allow the end to be passed downwardly between the guide rods 63 and thereafter is opened up and drawn over and about the sections of the mandrel to the point where the operating set of feeding and pressure rollers in each section engaged the material. The sections of the mandrel are set to properly distend the tubular material and the feed mechanism and cutter device are set in motion. As in other machines of this character, the material, due to the feeding mechanism, is simultaneously fed onto the mandrel and turned relative thereto to effect the spiral feeding and spiral cutting of the same for the purpose specified. When it is desired to provide a cut running in the opposite or, for example, counter-clockwise direction, the drive to the feeding mechanism is interchanged and the

cutting attachment is moved to its other supported position, in which case the rail B will revolve in the reverse direction and the material A will be drawn downwardly in a reverse spiral movement over the mandrel and in the path of the cutting disc.

In Figure 5 there is shown a bale 76 for a roll B of very great width, comprising a raised mid portion 77 in the closed part of the bale, which portion carries the rollers 78 running on the track 75. This arrangement allows greater length for the outer portions of the closed part of the bale beyond the raised portion 77 carrying the rollers 78, than in the construction shown in Figures 1 and 2.

The mandrel shown in Figures 6 and 7 comprise U-shaped sections 79 and 80, the flat sides 81 of each of which joins with the corresponding flat sides of the other to form the full flat sides of the mandrel. In this arrangement each flat side 81 of each section 79—80 is provided with an oblique opening 82 to accommodate the feeding and pressure rollers of the feeding mechanism and in the curved or U-shaped portion of the fixed section 79 of the mandrel is a cross-shaped slot 83 to receive the cutting disc of a cutting attachment.

Figure 8 shows one of the two sections 17—21 of a mandrel of the type used in the construction of Figures 1 to 4, except that the flat side of each section is provided with a single oblique opening 84 in its mid-portion and directly under it a single slot 85, the opening 84 receiving the feeding and pressure rollers of the feeding device and the slot 85 receiving the cutting edge of the disc of the cutting attachment.

It will be seen that in all forms of the present invention the feeding operation for moving the tubular material over the mandrel in a spiral direction is effected on the flat sides of the mandrel.

Having described my invention and the manner in which the same operates, what I claim and desire to secure by Letters Patent is:

1. In a bias cutting machine of the character described, the combination of a mandrel comprising a fixed flat section and a movable flat section over which a tubular material is adapted to be spirally fed, means on the flat sections engaging said material for feeding the same spirally thereover, and a cutting element for cutting a spiral strip from said material.

2. In a bias cutting machine of the character described, the combination of a mandrel over which a tubular material is fed, comprising substantially flat sections, one thereof being stationary, means for adjustably supporting the other section to allow for adjustment in the size of the mandrel, means arranged on the flat sections of the mandrel to engage said material for feeding the same spirally thereover, and a cutting element for cutting a spiral strip from said material.

3. In a bias cutting machine of the character described, the combination of a mandrel over which a tubular material is fed, comprising a fixed section and a movable section, each section having a flat side, alternate means operating in the flat sides of the sections and engaging said material for feeding the same spirally in one direction or the other over the mandrel, and a cutting element intermediate the alternate means for cutting a spiral strip from said material.

4. In a bias cutting machine of the character described, the combination of a mandrel over

which a tubular material is fed, comprising a fixed U-shaped section and a movable U-shaped section, the open ends of the two sections facing each other, the closed ends of the sections being flat, alternate obliquely-disposed means operating in the flat sides of each section and engaging said material for feeding the same spirally in clockwise or counterclock-wise direction over the mandrel, common driving means for operating alternate engaging and feeding means of both sections, and a cutting element for cutting a spiral strip from the material in either direction of movement thereof.

5. In a bias cutting machine of the character described, the combination of a supporting base having guide rails running between standards, a carriage mounted for movement over said rails, a mandrel over which a tubular material is fed, comprising substantially flat sided U-shaped sections arranged with their open ends facing each other, means for supporting the two sections on one standard of the base and the carriage respectively, two pairs of obliquely-disposed feeding and pressure rollers operating in the flat side of each section for engaging the said material for feeding the same spirally thereover in either clock-wise or counterclock-wise direction, driving means operating between the standards and capable of alternate connections with one pair of rollers in each section to rotate the feed rollers, and a cutting element for cutting a spiral strip from the material in either direction of movement thereof.

6. A bias cutting machine, as claimed in claim 5, in which the fixed section of the mandrel is provided with slotted openings to receive the cutting element, which comprises a rotary driven disc inclined in the direction of the slotted opening, and means for interchangeably supporting the said cutting element to allow for cutting the spiral strip of the material in the direction of its travel over the mandrel.

7. A bias cutting machine, as claimed in claim 5, in which said driving means for the feeding and pressure rollers comprises a rotary shaft, bearings on the standards and carriage to support the shaft, gear connections with the shaft at the standard carrying the fixed section of the mandrel and at the carriage, the connection at the carriage being arranged to rotate and move axially of the shaft to allow adjustment of the carriage, a universal connection with each set of gears, and means to unite the connection with one or the other of the oblique feeding rollers to drive one thereof and feed the material spirally over the mandrel.

8. A bias cutting machine, as claimed in claim 5, including means for supporting the feed rollers on the inside of the mandrel sections, and means carried by the standard carrying the fixed section and by the carriage to support the pressure rollers in contact with their respective feed rollers, said last means permitting each pressure roller to be moved out of contact with its feed roller.

9. A bias cutting machine, as claimed in claim 5, in which each mandrel section in its flat side is provided with a pair of oblique openings the longitudinal axes thereof converging downwardly towards each other, a pair of said rollers operating in each opening, and an X-shaped slot intermediate the openings of the fixed section to accommodate the cutting element in its opposite positions.

10. In a bias cutting machine, the combination of a mandrel over which a tubular material

is fed, comprising a fixed and a movable section, each thereof being flat and arranged parallel to each other, an oblique opening in each section, means in and at said openings engaging said material for feeding the same spirally over the mandrel, and a cutting element for cutting a spiral strip from said material.

11. A bias cutting machine, as claimed in claim 10, including a slot in the fixed section of the mandrel to accommodate the cutting element, said slot being disposed below the oblique opening and in the path of the material fed from the first means.

12. In a bias cutting machine of the character described, the combination of a mandrel comprising a curved fixed section and a curved movable section, over which a tubular material is adapted to be spirally fed and cut, means on the sections engaging said material for feeding the same spirally thereover in clockwise or counter-clockwise direction, and a cutting element arranged for cutting a spiral strip from said material during its spiral movement in either of said directions.

13. In a bias cutting machine, the combination of a pair of flat sections forming a mandrel, each section having an elongated slot disposed at an angle to the perpendicular, a pair of rollers carried by each section and operating at and in said slot to feed material over the mandrel, the common tangent of the pair of rollers coinciding with the outer surface of the flat section, and cutting means to sever the moving material into a bias strip.

14. In a bias cutting machine, the combination of flat sections forming a mandrel, rollers in the sections for feeding material in a spiral path over the mandrel, and means for cutting the moving material into a bias strip.

15. In a bias cutting machine of the character described, the combination of a mandrel comprising a fixed section and a movable section, each thereof having a flat side over which a tubular material is adapted to be spirally fed,

rollers for each section having their common tangent coinciding with the surface of the flat side of the section and feeding the material spirally thereover, and a cutting element for cutting a spiral strip from said material.

16. In a bias cutting machine of the character described, the combination of a mandrel over which a tubular material is fed, comprising substantially U-shaped sections arranged with their open ends facing each other, one section being stationary, means for adjustably supporting the other section to allow for adjustment in the size of the mandrel, rollers on opposite sides of each section engaging said material for feeding the same spirally thereover, the common tangent of the rollers of each section coinciding with the outer surface of the latter, and a cutting element at the fixed section for cutting a spiral strip from said material.

17. In a bias cutting machine of the character described, the combination of a mandrel comprising a fixed section and a movable section, over which a tubular material is adapted to be spirally fed and cut, means engaging said material for feeding the same spirally thereover in clockwise or counter-clockwise direction, and a cutting element arranged for cutting a spiral strip from said material during its spiral movement in either of said directions.

18. In a bias cutting machine of the character described, the combination of a mandrel over which a tubular material is fed, comprising a fixed and a movable section, each thereof being U-shaped in transverse section with flat closed sides and arranged with their open ends facing each other, an oblique opening in the closed flat side of each section, rollers in and at said openings engaging said material for feeding the same spirally thereover and having a common tangent coinciding with the outer surface of the section, and a cutting element for cutting a spiral strip from said material.

DAVID BALK.
